(57) CLAIM

The ornamental design for a brush with a thin handle, as shown and described.

DESCRIPTION

The claimed brush with a thin handle is used for cleaning shoes and clothing.

FIG. 1 is a top plan view of a brush with a thin handle showing my new design;

FIG. 2 is a front elevational view thereof, the rear being a mirror image;

FIG. 3 is a left side elevational view thereof, the right side being a mirror image; and,

FIG. 4 is a perspective view thereof.
